UNITED STATES PATENT OFFICE.

CLIFTON D. PETTIS, OF CHICAGO, ILLINOIS

BRAKE-SHOE.

1,104,925.

Specification of Letters Patent. Patented July 28, 1914.

Application filed July 24, 1912. Serial No. 711,304

To all whom it may concern:

Be it known that I, CLIFTON D. PETTIS, a citizen of the United States, and a resident of the city of Chicago, county of Cook, and State of Illinois, have invented certain new and useful Improvements in Brake-Shoes, of which I do declare the following to be a full, clear, and exact description, reference being had to the accompanying drawings, forming part of this specification.

My present invention has relation more particularly to that class of brake shoes for railway cars in which the back portion of the shoe is strengthened by a plate or rods of soft steel or like ductile metal preferably embedded in the body of the cast iron of the shoe in the casting operation. Examples of this type of shoe are illustrated in Letters Patent No. 892,883, granted to me July 7, 1908.

It is a fact well recognized by those familiar with the manufacture and use of brake shoes for railway cars, that the weakest parts of brake shoes are apt to be the lugs by which the shoes are engaged by the brake heads, or points immediately adjacent thereto. For this reason, various attempts have heretofore been made to reinforce or strengthen the lugs of brake shoes and to provide improved means for connecting such lugs to the ductile metal backs of the shoe.

Broadly stated, the object of the present invention is to provide an exceedingly strong, rigid, durable and effective construction of brake shoe lug and one which may be most effectively and securely fastened to the steel back or reinforcing rods of the shoe.

A further and specific object of this invention is to provide an improved construction of center lug whereby the brake shoe is connected at its center by a key to the brake head.

In an application filed by me of even date herewith, Serial No. 711,305, I have shown the broad features of the present invention as applied to the production of an improved construction of end lug for the brake shoe, and such end lug is specifically claimed in said companion application.

My present invention consists in the features of novelty hereinafter described, illustrated in the accompanying drawings and particularly pointed out in the claims at the end of this specification.

Figure 1 is a view in side elevation of a

brake shoe embodying my invention. Fig. 2 is a plan view. Fig. 3 is a detail view of the blank from which my improved center lug will be formed. Fig. 4 is a detail plan view of the central portion of the reinforcing back plate for the shoe. Fig. 5 is a view in cross section on line 5—5 of Fig. 2. Fig. 6 is a view in cross section on line 6—6 of Fig. 5. Fig. 7 is a view in longitudinal section on line 7—7 of Fig. 5. Fig. 8 is a view similar to Fig. 5, but showing the invention applied to a brake shoe having reinforcing rods. Fig. 9 is a detail view showing a central attaching lug formed as a malleable casting. Fig. 10 is a view showing the lug illustrated in Fig. 9 in position for use upon the brake shoe. Fig. 11 is a detail plan view of the central portion of the reinforcing back designed to receive the lug shown in Fig. 9.

My present invention will be found susceptible of application to a variety of reinforced brake shoes, to several of which it is shown as applied in the accompanying drawings. The body portion 20 of the brake shoe may be formed of cast metal, in the usual manner.

Referring to Figs. 1 to 7 of the drawings, 21 designates the strengthening back plate of the shoe, that will be embedded in the body of the shoe during the casting operation and after the attaching lug 22 has been attached to the back plate in the manner to be presently set forth. The attaching lug 22 is formed of ductile metal, such as soft steel, or a malleable casting.

In the form of the invention illustrated in Figs. 1 to 8 of the drawings, the attaching lug is shown as formed from a metal plate. Preferably, when the attaching lug is thus formed from a metal plate, the blank will first be cut to approximately the shape shown in Fig. 3 of the drawings. As shown, the back plate 21 is formed at each side of its longitudinal center with two openings 23 and 24, through which will pass respectively the locking members 25 and 26 that project downwardly from the side portions of the lug 22.

Each of the locking members 25 is formed adjacent its free end with an opening 25a and each of these locking members 25 is formed integral with the corresponding side wall 27 of the attaching lug, the side walls 27 being integral with the crown 28 of the lug. The side portions of the attaching lugs

are U-shaped, or of channel form in cross section (see Fig. 6), this being accomplished by forming each of the side walls 27 of the lug with laterally projecting brace walls or extensions 30. Integral with the walls or extensions 30 are formed the base portions 31 of the lug which, when brought together, as shown in Fig. 7, of the drawings, completely fill the space between the walls or extensions 30, and the locking members 26 are formed integral with the base portions 31. When the attaching lug is in position for use upon the back plate 21, the locking members 25 will be bent outwardly, as shown in Fig. 5 of the drawings, and the locking members 26 extend through openings 25^a of the locking members 25 and will have their free ends bent in opposite directions, as clearly shown in Fig. 7 of the drawings.

20 When my improved locking lug is to be formed from plate metal, the blanks, cut to the shape shown in Fig. 3, will be bent so that the side walls 27 shall extend at approximately right angles to the crown 28 of the lug. The brace walls or extensions 30 will be bent at approximately right angles to the side walls 27 of the lug and the base portions 31 will be bent to approximately horizontal position, so as to fill the spaces 30 between the brace walls or extensions 30, (see Fig. 7). The locking members 26 will be brought together and turned down to a position approximately at right angles to the base portions 31. The locking members 35 25 and 26 will then be passed through the openings 23 and 24 of the back plate 21, after which the locking members 25 will be bent outwardly so that the locking members 26 will extend through the holes 25^a of the locking members 25 and then the free ends of the locking members 26 will be bent in opposite direction, as shown in Fig. 7, and firmly forced against the under side of the locking members 25. By dotted lines in Fig. 45 3 of the drawings, I have indicated approximately the lines on which the blank there shown will be bent to form the completed attaching lug. Preferably, the locking members 25 after they have been bent outwardly, 50 as shown in Fig. 5 of the drawings, will have their free ends bent downwardly so that the cast metal, of which the body 20 of the shoe is formed, will flow around the free ends of the locking members 25 and thus 55 effectively guard against any possibility of the disengagement of the locking members. If desired, after the center lug has been attached to the back plate and the locking members 25 and 26 have been interlocked, as shown in Fig. 5, the parts may be electrically welded, or otherwise welded by any of the familiar methods suitable for such purpose.

By reference to Fig. 7 of the drawings, it 65 will be observed that each of the side portions of my improved lug are tapering in

cross section, that is to say, the base of each of the side portions is broader than the top of such side portions. This not only enables the lug to more properly engage the standard construction of brake head, but also materially strengthens the structure of the lug.

70 My invention presents numerous features of advantage, many of which will be found applicable to attaching lugs for brake shoes whether other features of the invention be employed or not. Thus, by forming the side portions of the attaching lug of U-shape in cross section, very great strength is given to the lug and the necessity for reinforcing the side walls of the lug by cast 80 metal is avoided. So, also, by extending a wall of metal (as by the base portions 31) between the brace walls or extensions 30, these walls 30 are materially strengthened and the metal between these walls 30 also 85 serves to effectively brace the side walls 27 of the lug. Again, by forming the attaching lug with locking members which extend through the reinforcing plate of the brake shoe and interlock with each other at two 90 points at each side of the longitudinal center of the shoe, much greater rigidity of attachment between the lug and the reinforcing back plate is secured than would be possible with a single locking member. So, 95 also, by providing the attaching lug with locking members which pass through the reinforcing back plate and interlock with each other on the under side of such plate, all danger of the attaching lug becoming 100 loose or disengaged from the back plate is effectively prevented. I believe that not only does my improved attaching lug afford a much stronger, more durable and more effective means for attaching the brake shoe 105 to the brake head than with prior constructions, but inasmuch as the attaching lug requires no cast metal reinforcement, the weight of the shoe is materially lessened. Other features of advantage incident to 110 my invention, or parts thereof, will readily occur to those familiar with this class of devices.

In Fig. 8 of the drawings, I have shown how my invention may be applied to brake 115 shoes of that type in which reinforcing rods 40 extending longitudinally of the shoe are employed to strengthen the shoe—this being one familiar way of reinforcing the backs of brake shoes. The manner of connecting 120 my improved attaching lug to the rods 40 will be readily understood from Fig. 8 and need not be more particularly described. It will be understood also that in forming a 125 brake shoe embodying my invention the attaching lug will first be connected to the reinforcing back plate or strengthening rods of the shoe, after which these parts will be placed in a mold and the body of cast metal will be cast upon or around the back plate 130.

or rods in manner well understood by those familiar with the manufacture of brake shoes.

In Figs. 9 to 11 of the drawings, I have shown my improved attaching lug as formed of a malleable casting. In this form of the invention, all the parts will be formed integral and the crown 28, the side walls 27, the brace walls 30 and the locking members 25 will be of substantially the shape hereinbefore described, the locking members 25 having openings 25^a adjacent their ends to receive the locking members 26^a. But in this form of the invention the base portion 31^a at each side of the attaching lug will extend between and be cast integral with the corresponding brace walls 30 and from the underside of each of these central portions 31^a a single locking member 26^a is shown as depending, instead of the two locking members 26 in the form of the invention hereinbefore described. When the locking members 25 and 26^a have been inserted through the openings of the back plate 31, in manner hereinbefore described, the locking members 25 will be bent outwardly, as shown in Fig. 10, so that the locking members 26^a will pass through the openings 25^a of the locking members 25, after which the free ends of the locking members 26^a will be bent laterally, as shown.

It is obvious that the precise details of the construction above set out may be varied within wide limits without departing from the spirit of the invention, and that features of the invention may be employed without its adoption as an entirety.

Having thus described my invention, what I claim as new, and desire to secure by Letters Patent, is:

1. The combination with a brake shoe, of a lug formed of an integral piece of ductile metal having a crown, side walls, brace walls integral with said side walls and extending laterally therefrom at the edges thereof whereby a channel-shaped formation is given to the side portions of the lug, laterally extending base portions between said brace walls, and locking members at each side of the lug.

2. The combination with a brake shoe, of a lug formed of ductile metal having a crown, side walls extending from said crown to the back of the shoe, brace walls integral with and projecting laterally from each of said side walls, and locking members integral with and projecting from said brace walls.

3. The combination with a brake shoe, of a lug formed of ductile metal having locking members projecting therefrom and arranged to interlock one with the other.

4. In a brake shoe, the combination with a reinforcing back, of a lug provided with a plurality of locking members engaging

said reinforcing back and interlocked with each other.

5. The combination of a brake shoe having a back plate and an attaching lug formed of ductile metal and having a crown 70 and side walls, and locking members outside of said side walls and extending through the back plate of the shoe, the free ends of said locking members being bent to interlock with said back plate.

6. The combination with a brake shoe, of a back plate provided adjacent its center with four openings and an attaching lug formed of an integral ductile metal plate, said lug having base portions, a crown and side walls extending between the crown and back plate, locking members integral with said side walls and extending through said back plate, and locking members integral with said base portions and extending 85 through said back plate.

7. A brake shoe comprising a cast metal body, a reinforcing member therein, and a center attaching lug made of ductile metal, 90 said lug having a crown, side walls at opposite sides of the crown, brace walls extending laterally and integral with each of said side walls, and locking members connecting the side portions of the lug with said reinforcing member.

8. The combination with a brake shoe of an attaching lug made of ductile metal and comprising a crown and side walls formed integral with said crown, each of said side walls having brace walls extending laterally 100 from and integral therewith and at substantially right angles to said side walls.

9. The combination with a brake shoe of an attaching lug formed of ductile metal and having side portions provided each 105 with a plurality of locking members for attaching the lug to the shoe.

10. The combination with a brake shoe of an attaching lug formed of ductile metal and having a crown and side walls and base 110 portions integral with the crown, and locking members extending from said base portions.

11. The combination with a brake shoe of an attaching lug formed of ductile metal 115 and having side portions each provided with a plurality of locking members, one of said members being cut away to receive the other of said members.

12. The combination with a brake shoe of an attaching lug formed of ductile metal and having side portions each provided with two depending locking members, one of said locking members having a hole adjacent its end adapted to receive the other of said 125 locking members.

13. The combination with a brake shoe of an attaching lug formed of ductile metal and having side portions each formed of a side wall, laterally projecting brace walls 130

integral with said side walls, base portions integral with said brace walls and depending locking members certain of which are integral with said side walls and others of 5 which are integral with said brace walls.

14. In a brake shoe, the combination with a cast metal body and a reinforcing back, of an attaching lug having side portions each

of which is formed with a plurality of depending locking members engaging said re- 10 inforcing back, and interlocked with each other.

CLIFTON D. PETTIS.
